(57) **CLAIM**

The ornamental design for an inhaler as shown and described.

DESCRIPTION

FIG. 1 is a top, front, and left side perspective view of an inhaler, showing my new design;

FIG. 2 is a top view thereof;

FIG. 3 is a right side view thereof;

FIG. 4 is a bottom view thereof;

FIG. 5 is a left side view thereof;

FIG. 6 is a front view thereof;

FIG. 7 is a rear view thereof;

FIG. 8 is a longitudinal cross-sectional view along the line 8-8 in FIG. 2;

FIG. 9 is an oblique cross-sectional view along the line 9-9 in FIG. 2;

FIG. 10 is a longitudinal cross-sectional view along the line 10-10 in FIG. 6;

FIG. 11 is a horizontal cross-sectional view along the line 11-11 in FIG. 6;

FIG. 12 is a top, front, and left side perspective view of the inhaler, shown in an open configuration;

FIG. 13 is a top view thereof;

FIG. 14 is a right side view thereof;

FIG. 15 is a bottom view thereof;

FIG. 16 is a left side view thereof;

FIG. 17 is a front view thereof;

FIG. 18 is a rear view thereof;

FIG. 19 is a longitudinal cross-sectional view along the line 19-19 in FIG. 13;

FIG. 20 is an oblique cross-sectional view along the line 20-20 in FIG. 13;

FIG. 21 is a longitudinal cross-sectional view along the line 21-21 in FIG. 14;

FIG. 22 is a horizontal cross-sectional view along the line 22-22 in FIG. 16; and,

FIG. 23 is a longitudinal cross-sectional view along the line 23-23 in FIG. 16.

The areas shown in broken lines depict portions of the inhaler that form no part of the claimed design.

1 Claim, 23 Drawing Sheets
